UNITED STATES PATENT OFFICE

LLOYD M. WILLIAMS, OF CHICAGO, ILLINOIS, ASSIGNOR TO LLOYD'S MFG. CO., OF CHICAGO, ILLINOIS, A CORPORATION OF ILLINOIS

DESIGN FOR A ROTARY ACCELERATOR PEDAL

Application filed August 12, 1929. Serial No. 32,392. Term of patent 14 years.

To all whom it may concern:

Be it known that I, LLOYD M. WILLIAMS, a citizen of the United States, residing at Chicago, in the county of Cook and State of Illinois, have invented a new, original, and ornamental Design for Rotary Accelerator Pedals, of which the following is a specification, reference being had to the accompanying drawings, forming part hereof, wherein—

Figures 1, 2 and 3 are, respectively, a side elevation, a front elevation, and a top plan view of a rotary accelerator pedal showing my new design.

I claim:

The ornamental design for a rotary accelerator pedal as shown.

LLOYD M. WILLIAMS.
